UNITED STATES PATENT OFFICE

EDGAR W. REUTENER, OF CLEVELAND, OHIO, ASSIGNOR TO THE WM. A. HOWE COMPANY,
OF CLEVELAND, OHIO, A CORPORATION OF OHIO

DOOR OSCILLATING DEVICE

Application filed February 5, 1932. Serial No. 591,102.

This invention relates to a device which is particularly adapted to be secured beneath a refrigerator and to be connected with the door thereof in such a manner as to impart an opening and closing movement to the door for advertising purposes.

The main object of the invention is to provide a door oscillating device of the character described which is adapted to be positioned beneath the refrigerator in such a manner as to be out of view and to be connected with the refrigerator door so as to oscillate the same.

Another object of the invention is to provide a door oscillating device of the character described which may be quickly and readily secured beneath the refrigerator and which is well adapted for production at a low cost.

20. Further and more limited objects of the invention will appear as the description proceeds and by reference to the accompanying drawings in which Fig. 1 is a view partly in section and partly in elevation of a refrigerator having my door oscillating device connected therewith; Fig. 2 is a horizontal sectional view on the line 2—2 of Fig. 1 with the parts shown in the position in which they will appear with the door partially open; 30. Fig. 3 is a vertical sectional view on the line 3—3 of Fig. 1, and Fig. 4 is a fragmentary sectional view disclosing the manner of connecting the door operating means to the door.

Referring now to the drawings, the reference character 1 designates a refrigerator having a door 2 and legs 3, 4, 5 and 6. Disposed beneath the refrigerator and between the legs thereof is a base member 7 which is preferably rectangular in shape and provided with suitable legs 8. The base member 7 is of such size as to be inserted between the legs of the refrigerator and then turned to the position shown in Fig. 2. One corner of the base member fits into the angular leg 5, as shown in Fig. 2, and pivotally secured to the other corners thereof are bars or brackets 9, 10 and 11 which are adapted to be moved to the position shown in Fig. 2 to secure the base member against displacement. 50. Carried by the base member 7 is an annular

bearing member 12 which is secured thereto by bolts or rivets 13 and 14. Supported by the bearing member 12 is a disk or plate 15 to which is secured a boss or projection 16 which is held in place by bolts or rivets 17 and 18. The member 12, together with the boss 16, provides a sort of thrust bearing adapted to receive a ball bearing 19 which rotatably supports the disk 15. The disk 15 is provided about its periphery with an annular recess or depression 20 adapted to receive a belt therein the purpose of which will hereinafter appear.

Carried by the base member 7 is an electric motor M which drives a pulley 21 through suitable reduction gearing provided within a casing 22. The pulley 21 drives the disk 15 through the medium of a belt 16. The belt 16 extends about the periphery of the disk and fits within the peripheral recess 20. Also carried by the base member 7 is an idler pulley 23 which is carried by a bracket 24 pivotally secured to the base member by means of a pin 25. Also carried by the base member 7 is a pin 26 and connected therewith is a spring 27 the opposite end of which is secured to a pin 28 carried by the link 24. This idler pulley 23 serves to take up the slack in the belt and to provide an operative driving connection between the pulley 21 and the disk 15.

Disposed adjacent one side of the refrigerator is a supporting bar or bracket 29 which is of the same shape as the leg 5 and is secured thereto by means of clamps 30 and 31. Pivotally secured to the supporting member 29 is an angular link 32 which is held in place by brackets 34 and 35. Connected with one end of the link 32 is a U-shaped clamp or bracket 36 which engages the lower edge of the door 2 and which is provided with blocks 37 and 38 of rubber or other suitable material which serve to protect the surface of the door. Pivotally connected with the disk 15 is a link 39 one end of which is pivotally connected to one end of the link 32 by means of a pin 40 and the other end of which is connected with the disk 15 by means of a pin or bolt 41. Leading from the electric motor M is an electrical connection 42 which serves to connect 100

the motor with a suitable source of electric current.

The operation of the device is as follows: The motor M drives the pulley 21 through suitable reduction gearing enclosed within the casing 22. The disk or plate 15 is driven from the pulley 21 through the medium of the belt 16. The rotary motion of the disk 15 imparts an oscillatory movement to the refrigerator door 2 through the medium of the links 39 and 40 and the door is given an opening and closing movement so long as the motor is in operation. The entire mechanism is quickly and readily detached and moved from the refrigerator when desired. The apparatus is intended primarily for display purposes and is intended to be removed when the refrigerator is sold or otherwise disposed of. The apparatus consists of comparatively few parts which are cheap in construction and can be readily assembled or disassembled.

Various changes may be made in the shape, size and arrangement of parts without departing from the spirit of my invention and the embodiment of the invention herein disclosed is merely illustrative and the invention is limited only in accordance with the scope of the appended claims.

Having thus described my invention, what I claim is:

1. A door oscillating member for use with a refrigerator comprising a base member and means for securing the same between the legs of a refrigerator, a disk rotatably mounted on said base member, a motor operatively connected with said disk, a supporting member adapted to be secured to one leg of the refrigerator, an angular link pivotally secured to said supporting member and having one end adapted for connection with the refrigerator door and means operatively connecting the other end of said link with said disk whereby the rotary movement of said disk will impart an oscillatory movement to the refrigerator door.

2. A door oscillating device adapted for use with a refrigerator comprising a base member adapted to be positioned there beneath, a rotatable member carried by said base member, a motor carried by said base member and operatively connected to said rotatable member, a supporting member adapted to be secured adjacent said door, an angular link pivotally secured to said supporting member and having one end connected to said door, and operative connections between the other end of said link and said rotatable member whereby to oscillate said door.

3. A door oscillating device adapted for use with a refrigerator comprising a base member adapted to be positioned there beneath, a rotatable member carried by said base member, a motor carried by said base member and operatively connected to said rotatable member, a supporting member

adapted to be secured adjacent said door, an angular link pivotally secured to said supporting member and having one end connected to said door, operative connections between the other end of said link and said rotatable member whereby to oscillate said door, and means for securing said base between the legs of a refrigerator.

4. A door oscillating device comprising a base member adapted to be positioned beneath the door, a rotatable member carried by said base member, a motor operatively connected with said rotatable member for rotating the same, a supporting member adapted to be secured adjacent the door, an angular link secured to said supporting member and having one end connected to said door and its opposite end connected to said rotatable member whereby the rotary movement of the rotatable member will impart a continuous oscillatory motion to the door.

5. A door oscillating device comprising a base member adapted to be positioned beneath the door, a rotatable member carried by said base member, a motor operatively connected with said rotatable member for rotating the same, a supporting member adapted to be secured adjacent the door, an angular link secured to said supporting member and having one end connected to said door and its opposite end connected to said rotatable member whereby the rotary movement of the rotatable member will impart a continuous oscillatory motion to the door, the connection between said link and door including a U-shaped clamp adapted to engage the lower edge of the door.

6. A door oscillating device of the character described adapted for use with a refrigerator comprising a base member adapted to be spaced beneath the refrigerator, a rotatable member carried by said base member, a motor operatively connected to said rotatable member, a supporting member adapted to be detachably secured adjacent the door, an angular link carried by said supporting member and having one end connected to said door and its opposite end connected to said rotatable member whereby upon operation of the rotatable member a continuous oscillatory motion will be imparted to the door, the entire unit being self-contained and adapted to be removed from beneath the refrigerator as a unit.

In testimony whereof, I hereunto affix my signature.

EDGAR W. REUTENER.
